WISHING WELL

Edward L. Block, 1016 Hollywood Ave., Chicago, Ill.

Filed Nov. 30, 1959, Ser. No. 58,520

Term of patent 14 years

(Cl. D13—1)

Fig. 7.

removed and the fountain box and water tray extending partially and rearwardly thereof.

I claim:

The ornamental design for a wishing well, as shown.
